Primary Examiner — Susan E Krakower

Assistant Examiner — Michelle M Reeves

(74) Attorney, Agent, or Firm — Hawaii Patent Services;
Nathaniel K. Fedde; Kenton N. Fedde(57) **CLAIM**

The ornamental design for a footrest as shown and described.

DESCRIPTION

FIG. 1 is a top, front, right perspective view of a footrest, showing my new design;

FIG. 2 is a bottom, rear, right perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof;

FIG. 7 is a partial enlarged view of portion marked "7" FIG. 1;

FIG. 8 is a partial enlarged view of portion marked "8" FIG. 3;

FIG. 9 is a partial enlarged view of portion marked "9" FIG. 4;

FIG. 10 is a partial enlarged view of portion marked "10" FIG. 5;

FIG. 11 is a top, front, right perspective view of the footrest with the feet partially extended; and,

FIG. 12 is a bottom, rear, right perspective view of the footrest with the feet fully extended.

The dash-dash broken lines in the figures depict portions of the footrest, which form no part of the claimed design.

The dash-dot-dash lines depict the boundaries of the enlarged views, which form no part of the claim design.

1 Claim, 10 Drawing Sheets(56)
